UNITED STATES PATENT OFFICE.

CHARLES I. BODENSTEIN, OF ROCHESTER, NEW YORK.

VALVE-GRINDER.

1,371,142.

Specification of Letters Patent.

Patented Mar. 8, 1921.

Application filed April 4, 1919. Serial No. 287,526.

To all whom it may concern:

Be it known that I, CHARLES I. BODENSTEIN, a citizen of the United States, residing at Rochester, in the county of Monroe 5 and State of New York, have invented certain new and useful Improvements in Valve-Grinders, of which the following is a specification.

My invention relates to improvements in 10 valve grinders of the type used to grind the valves used in engines, motors, pumps, and other class of mechanisms where necessary to make the valve seat absolutely snug fitting.

One object of my invention is the production of a valve grinder which will have all 15 necessary adjustments to permit the device to operate from the most convenient position with reference to the valve and engine.

Another object of my invention is the provision of a device having accommodating 20 adjustments and imparting to the valve an oscillating motion to effect, in connection with a suitable abrasive, the grinding of the 25 valve and its seat and also having a lifting action to bodily raise the valve and allow the abrasive material to be drawn to the center of the ground surface of the valve seat by the suction caused by lifting the 30 valve.

Another object of my invention is the provision of a valve grinder which will permit only the required pressure to be applied to 35 effect the proper grinding action, and which will upon excess pressure being applied fail to operate.

Another object of my invention is the provision of a valve grinder which will be small 40 and compact to be easily stored and carried; which will be of simple, durable and inexpensive construction and which generally in all important respects will prove desirable, 45 efficient and practical.

To attain the objects stated and such others as reside in a device of this character the invention consists of a valve grinder embodying novel features of construction, combination, and arrangement of parts, substantially as shown, described and claimed 50 herein.

In the drawings:

Figure 1 is a view in elevation partly in section showing the manner of using my device.

Fig. 2 is a side elevation of the double

yoke and fork portion of the device viewed at right angles to that shown in Fig. 1.

Fig. 3 is a detail view of the valve and valve seat.

Fig. 4 is a detail perspective view of the 60 novel form of fork and double yoke construction and including the guide shank of my invention.

Fig. 5 is a detached perspective view of 65 the sleeve.

The valve grinder is of very simple construction and consists of a handle A, a fork B, formed on threaded shank C, having reduced stem D, fitting in socket E; tube F; upon said stem, coiled spring G; and nuts 70 H, for adjusting said spring, the stem D carrying a pin D', adapted to engage recesses E', of the tube F, to lock the shank and prevent turning of said shank.

From this construction it will be seen that 75 the turning of the handle imparts a similar movement of the shank and the fork, and in the fork is pivotally mounted at J the lower ends of the yoke B, while rigidly secured to the yoke at I, is the yoke-shaped 80 valve grip M, whose pair of spring arms tend outward at their extremities N, to spring into the standard openings O, in valve P adapted to fit the valve seat Q of the 85 engine.

In operation a suitable abrasive material is placed between the valve and its seat and the spring yoke is fitted to the valve, in which position the handle is manipulated with an oscillating movement either in a 90 vertical or inclined position, to turn the valve and produce a smooth and even face between the valve and its seat, this oscillating movement causes the abrasive to accumulate at the edges of the valve and when 95 accumulation occurs it is only necessary to lift the handle and with it the valve from its seat and this action causes the accumulation to be sucked to the center of the valve seat thus renewing the proper amount of 100 abrasive material. At the same time the valve is raised to renew the abrasive, by the action of the suction, the valve is given a part turn to insure an even distribution of 105 the abrasive around the circumference of the valve seat and also an even distribution of the wear caused by the abrasive. The valve should be lifted frequently during the operation of grinding to insure a complete 110 renewal of accumulated abrasive and the

grinding of smooth surfaces, and only a moderate pressure is required to obtain the best results, the releasing attachment and adjustable spring insuring the proper pressure to obtain the best results.

The abrasive mixed with material ground from the valve and the engine, must be removed occasionally and new abrasive applied.

- 10 Good practice in grinding valves requires that the valve be oscillated approximately five or six times, then raised and given a part turn, this operation repeated from ten to twenty times when the abrasive and ground material should be removed and new abrasive applied.

If the valve is oscillated too many times the pressure applied on the last few particles of the abrasive grinds a groove around the 20 circumference of the valve seat which is destructive to the proper action of the valve.

I claim:

1. A valve grinder comprising a handle, a movable shank mounted in said handle, a 25 fork at the end of the shank, a double yoke valve engaging member mounted in said

fork, means for preventing movement of the shank with reference to the handle, and means whereby the valve engaging member may have a swinging movement with reference to the valve.

2. A valve grinder comprising a handle, a movable shank mounted in said handle, a fork at the end of the shank, a double yoke valve engaging member mounted in said 30 fork, means for preventing movement of the shank with reference to the handle, and means whereby the valve engaging member may have a swinging movement with reference to the valve, there being a flexible 35 connection between the shank and the valve engaging member.

3. A valve grinder consisting of a handle, a shank carrying the said handle, a valve 40 engaging member swingingly mounted in said shank and having spring arms to engage notches in the head of the valve to permit manipulation of the valve from different positions with reference to said valve.

In testimony whereof I affix my signature. 50

CHARLES I. BODENSTEIN.
